WARP KNITTING MACHINE

Lambertus te Strake, Deurne, Netherlands

Application February 6, 1947, Serial No. 726,920
In the Netherlands November 12, 1946

11 Claims. (Cl. 66—87)

1

This invention relates to textile machines, and more particularly to warp knitting machines, by means of which zigzag knitted fabric may be manufactured.

According to the invention for two series of latch needles moving alternately in the directions of the needles by two series of thread guides moving to and fro in opposite directions first two intercrossing threads are presented to each needle of the one series and thereupon also two intercrossing threads are presented to each needle of the other series, in such a manner, that the intercrossing threads will be put simultaneously in pairs in the respective threads of the needles, are closed in by the latches, are simultaneously drawn through previously made stitches and are shoved onto the necks of the needles, which thread crosses, moreover, may be presented each time to different needles of the series, in such a way that a zigzag knit fabric is obtained.

In order to supply the outer needles with warp yarn, when these at a certain moment no longer receive any warp yarn, according to the invention separate auxiliary or additional warp yarns may be supplied to the outer needles of each series for making a warp knitted fabric as longitudinal edges of the proper or main knitted fabric.

At the same time thereby a good selvedge against fraying may be obtained. For presenting the auxiliary warp yarn in absence of crossed threads a periodic supply of auxiliary warp yarn to the edges might be sufficient. For the knitting of the selvedge the auxiliary yarn must always be supplied to the edges.

All the above mentioned warp yarns may be supplied from warp beams, on which they are warped corresponding to the desired zigzag and colors. This does not alter the fact that all warp yarns may be of the same color.

In order to take away wholly or partially the width elasticity of the knitted fabric or for the purpose of extra patterning, or for both purposes, according to the invention, moreover, one or more weft threads may be supplied to the reciprocating needles by means of one or more thread guides moving to and fro parallel to the series of knitting points.

The inventive thought comprises also modifications and improvements as well as technically equivalent embodiments of the warp knitting machine.

A flat warp knitting machine according to the invention may comprise two series of latch needles movable up and down in the direction of their longitudinal axis and two series of thread

2

guides movable longitudinally of the series of needles which are governed in such a manner, that first they form thread crosses at the places for the needles of the one series and then at the places for those of the other series, whereas the thread crosses are offset in such a way that a zigzag knitted fabric results.

A warp knitting machine according to the invention may be used for the manufacture of knitted fabrics having a front and a back or having at both sides equally good front appearance. Furthermore, it is possible to form various designs in a simple manner and with simple means without using a Jacquard machine and without using knitting cams, spring beard needles or closed eye needles.

A knitted fabric manufactured by a warp knitting machine according to the invention possesses the favorable property of automatically blocking laddering.

The invention not only applies to the working of normal knitting yarns, but also permits zigzag knitting of coarse and hard yarns. The machine may be constructed for each knitting width, whereas on a machine with great width also small fabrics may be knitted.

Shawls and fabrics for outerwear are examples of knitted fabrics, which may be knitted by a warp knitting machine according to the invention.

Other objects and structural details of the invention will be apparent from the following description when read in conjunction with the accompanying drawings illustrating only one example of embodiment, to which the invention by no means is restricted. In the drawings:

Fig. 1 is a front elevational view on a small scale of a zigzag warp knitting machine according to the invention.

Fig. 2 is a side elevational view of the right hand side of the machine.

Fig. 3 is a side elevational view of the left hand side of the machine.

Fig. 4 is a fragmentary vertical sectional view of the upper portion of the machine, said sectional view being taken, parallel to the right hand side of the machine,

Figs. 5, 6, 7 and 8 illustrate diagrams of the operations of the machine,

Fig. 9 is a fragmentary front elevational view of the drive associated with the warp yarn guide bars of the machine,

Fig. 10 is a fragmentary side elevational view of the upper portion of the left hand side of the machine.

Fig. 11 is a fragmentary front elevational view of the upper portion of the left hand side of the machine,

Fig. 12 is a fragmentary front elevational view of the upper portion of the machine, illustrating the needle beds and the warp yarn guide bars,

Fig. 13 is a fragmentary front elevational view of the upper portion of the machine, illustrating the mechanism for laying weft threads,

Fig. 14 is a sectional view of the upper portion of the needle beds, illustrating one of the weft thread carriers in its operative position,

Fig. 15 is a fragmentary front elevational view of the machine illustrating an automatic device for controlling the movements of the weft thread carriers,

Fig. 16 is a side elevational view of the mechanism shown in Fig. 15,

Fig. 17 is a diagrammatical illustration of a zigzag knitted fabric manufactured by a machine according to the invention, and

Fig. 18 is an elevational view of a cam mechanism controlling the movements of the warp yarn guide bars.

Referring now to Figs. 1-3, the flat warp knitting machine according to the invention comprises a frame, including a right hand side piece 1, a left hand side piece 2 and connecting pieces 3 connected with each other. In this frame an electromotor—not shown—is arranged for driving continuously the main shaft 4 of the machine. Warp beams, 5, 5, 6, 6, 7, 7, are rotatably arranged on the frame for the supply of yarn to the needles as required for the knitting of the zigzag knitted portion of the fabric and of the edges of the fabric. The yarns coming from the four first-mentioned warp beams pass over a series of thread guides supported by arms 8, 9. The thread guides of the arms 9 are pivotally mounted on shafts and are pressed sideways by helical springs, by means of which the yarn tension can be controlled. The yarn is warped on the warp beams in correspondence with the desired pattern and color arrangement and is supplied in the correct arrangement to the machine by the thread guides.

As best shown in Figs. 4 and 14, the machine comprises two separate frame pieces 10, 20 for two different needle beds 11, 21, arranged at a sharp angle with respect to each other. 11 indicates the back needle bed and 21 indicates the front needle bed.

In the back needle bed 11 latch needles 12 are slidably guided in the direction of their longitudinal axis. They are jointly and removably arranged in a holder 13 closed by a cover plate 14. The holders 13 slidably engaged with guiding members 15 mounted on the frame are provided at their ends with pins slidably engaged with slots arranged in the side walls of the frame. The pins of the holders 13 passing through said slots project somewhat outside said side walls. The projecting ends of said pins are engaged with a needle drive to be described hereinafter, by means of which the holders 13 with the needles mounted therein may be moved upwardly and downwardly. The needles are held in place at the upper ends of their shanks by a pressure bar 16 with felt cushion 17, which prevents the needles from tilting. Springs act on the ends of the pressure bar in such a manner, that the felt cushion keeps the needles in place and guides them properly. A warp guide 18 in the shape of a bar slidably arranged above the series of knitting points for the needles of the back needle bed 11 is recipro-

cable longitudinally of the machine and serves as a guide for the warp yarns 19 coming from the warp beams 5, 5. The guiding means proper of the warp guides 18 are formed by V-shaped grooves cut into longitudinal ribs arranged on the bar 18, one for each yarn, therefore one for each needle of the back needle bed 11. Corresponding parts of the front needle bed and the mechanisms associated therewith are indicated by the reference numerals 21-29; 21 indicates the front needle bed, 22 the front needle, 23 the holders, 24 the cover plate, 25 the guiding members, 26 the pressure bar, 27 the felt cushion, 28 the warp guide and 29 the warp yarns. The latch needles 12 of the back needle bed 11 are lying with their paths of operation of their heads midway between the latch needles 22 of the front needle bed 21, so that in the series of knitting points a head of a front needle 22 alternates with a head of a back needle 12. The guiding grooves of the warp guide bars 18 and 28 face the same side of the machine, i. e., the front side in the embodiment shown in Fig. 4.

In order to cause the series of needles to catch yarn alternately, the front needles and the back needles are carrying out opposite movements. The warp guide bars 18, 28 perform horizontal opposite movements in such a manner that the yarns guided by one bar are crossing those guided by the other in the plane of either the front needles or the back needles as shown diagrammatically in the Figs. 5 to 8 inclusive.

In Fig. 5 the needles 12 of the back bed are in their highest position and the needles 22 of the front bed are in their lowest position. The crossing points of the warp yarns, hereinafter called the warp yarn crossings, formed by the position of the warp guides 18, 28, are ready for being drawn downwardly by the needles 12 of the back bed, towards the position shown in Fig. 6.

In Fig. 6 the needles 12 of the back needle bed are moved downwardly into a position at a distance of $\frac{1}{4}$ of the stroke away from their lowest position and the needles 22 of the front needle bed are moved upwardly into a position at a distance of $\frac{3}{4}$ of the stroke away from their lowest position. The needles of the back bed have pulled along with them the warp yarn crossings, so that there are no crossings any longer.

According to Fig. 7 the warp guide bar 18 is moved to the right and the warp guide bar 28 is moved to the left, relative to the position shown in Figs. 5 and 6, whereby new warp yarn crossings are formed. Contrary to Fig. 5, however, the warp yarn crossings are now formed adjacent to the needles of the front needle bed, said needles now being in their highest position, while the needles of the back needle bed are now in their lowest position.

According to Fig. 8 the warp guide bar 18 is moved towards the left and the guide bar 28 is moved towards the right. The needles 22 of the front needle bed have caught previously the warp yarn crossings and have pulled them downwardly during their movement into a position at a distance of $\frac{1}{4}$ of the stroke away from their lowest position. The needles 12 of the back needle bed are moved upwardly into a position at a distance of $\frac{3}{4}$ of the stroke away from their lowest position.

The warp guide bars 18 and 28 are governed in such a manner that during the next cycle they are moving each one step (one needle pitch) more to the left (or to the right) that is to say as many times subsequently as prescribed by the

pattern (the zigzag). Thereafter, they must be moved back in the corresponding manner, or, as in this example, they may return fully to the starting position. Thus, it is possible to have for a certain pattern a width of repeats of e. g. 24 needles (12 in the front bed and 12 in the back bed) with a pitch of 1.5 mm. The width of repeats then is $24 \times 1.5 = 36$ mm.

It will now be described how a machine according to the invention, operating corresponding to the diagrams of Figs. 5-8 may be constructed.

The drive of the needles.

As mentioned above the pins of the holders 13 (Fig. 4) holding the series of needles pass through slots arranged in the side walls of the machine parallel to the needle beds. The pins of the holder arranged in the front needle bed are driven in the same manner, but only in opposite direction, as the pin of the holder arranged in the back needle bed; the drive at the left hand side of the machine is the same as the drive at the right hand side of the machine; therefore, it is sufficient to describe hereinafter only the drive at the right hand side of the machine.

As best shown in Fig. 2, an eccentric sheave fixed to the main shaft 4 is operatively engaged with an eccentric strap, in the upper portion of which the left hand screw threaded lower end of a connecting rod 32 is screwed and locked by a counter-nut. The upper end of the connecting rod 32 is provided with right hand screw thread and screwed into the bridge piece of a fork 33 and locked. This fork carries a pin 34 slidably engaged with a slot 35 of the arm 36 of a two-armed oscillating lever 36, 37, which may oscillate around a shaft 38. Whereas the length of the stroke of the arm 36 of the lever 36, 37 may be roughly adjusted by an adjustment of the length of the connecting rod 32, an additional fine adjustment of the stroke of the arm 36 may be obtained by a displacement and fixing of the pin 34 in the slot 35. The lever 36, 37 is connected by adjustable connecting rods 39, 40 with the pins arranged at the ends of the needle holders 13. Upon rotation of the main shaft 4 the oscillating lever 36, 37 is oscillated and drives by the connecting rods 39, 40 the pins of the needle holders 13, which thus are moved upwardly and downwardly in the guiding members 15. By changing the length of the connecting rods 39, 40 relative to each other, the position of the front needles relative to the back needles may be changed. With the device as shown, therefore, an exact adjustment of the length of stroke of the front needles and of the back needles and the movement of the front needles and back needles relative to each other may be obtained in order to catch the warp yarn crossings properly.

The knitting of the selvedge

As best shown in Figs. 10 and 11, each arm 37 of each oscillatable lever 36, 37 drives through the medium of an adjustable connecting rod 41 an arm 42 keyed to a shaft rockably mounted in the frame of the machine. Furthermore, an arm 43 having a slot is keyed to said shaft, so that said arm 43 participates in the rocking movements of the arm 42. The lower end of an oscillatable lever 44 swingly mounted on the frame of the machine at 46 is adjustably engaged with the slot of said rockable arm 43. The upper arm 45 of said oscillatable lever 44 is pivotally connected at its upper end with one end of a connecting rod 47 of adjustable length. The other end of

said adjustable connecting rod 47 is connected to a slideable rod 48 carrying an auxiliary warp yarn guiding frame 49 to which auxiliary warp yarns wound on the warp beam 7 are supplied through a guiding rod and guiding comb or reed 50. This comb is swingable against the action of a torsion spring. The auxiliary warp yarns needed for the knitting of the selvedges pass from the frame 49 to the region of the moving needles. Both auxiliary frames supply the outer rows of latch needles or selvedge needles with yarns, at those places where warp yarn is not presented to the needles by above-described warp yarn crossings of the main warp yarns, so that a warp knit fabric is formed at the edges of the fabric.

If desired, at each side of the machine a weft thread supplied by a separate bobbin arranged at the front of the machine may be laid along the selvedge needles by means of a reciprocating weft thread guide.

A plurality of auxiliary frames 49 may be arranged on a carrier extending along the entire width of the needle bed, so that such auxiliary warp yarns may be presented to any desired needle of the needle beds.

The drive of the warp yarn guide bars.

As best shown in Fig. 9, cam drives are associated with the left-hand ends of the guide bars 18 and 28. Said cam drives are substantially of identical construction, they are merely displaced 180° in phase relative to each other. Therefore it is sufficient to describe only the cam control of the guide bar 28. By means of an adjustable rod 51 the left hand end of the guide bar 28 is connected to the upper arm 52 of a rockable rod 52, 53 fulcrumed at 54. The lower arm 53 of said rod carries a nose 56 held in engagement with a cam 57 by means of a spring 55 stretched between the arm 53 and the frame of the machine. As shown in Figs. 9 and 18, said cam 57 and the corresponding cam associated with the guide bar 18 are fixedly but replaceably mounted on a common shaft 58, which is driven continuously by the main shaft 4 through a suitable mechanism. The cam disc 57 is provided with teeth of spirally increased height in such a manner, that besides the reciprocating movement of the guide bar 28 a displacement thereof towards the plane of a next needle is caused, e. g. in the manner of a so-called pilgrim step. At the end the guide bar either may be operated in the reverse sense, or may be moved back into the starting position; according to the example illustrated by the drawings, the latter procedure takes place.

The adjustment of the length of the stitches

As shown in Figs. 2 and 3, a pair of drawing-off rollers 59, 59' is rotatably arranged in the lower portion of the knitting machine near the ground. Fabric knitted by the knitting implements may be clamped between said drawing-off rollers 59, 59' for effecting the drawing-off of the fabric.

The roller 59 is continuously driven by the main shaft 4 through the medium of gears as shown in the drawings. The length of the stitches may be adjusted by changing the drawing-off action of the rollers 59, 59' on the fabric, for example by replacing the gear mounted on one of the shafts by a larger gear or by a smaller gear, as the case may be, and by replacing at the same time the intermediate gear by another.

suitable gear. There is also a handwheel (Fig. 3) attached to a shaft of the roller drive for adjustment of the roller 59 by hand. In order to prevent a turning of the entire mechanism in advance of the gearing, a claw-coupling operative in one direction only is arranged in the roller drive. The shafts of the rollers 59, 59' are provided with pinions meshing with each other, so that both rollers are driven simultaneously.

The drive of the weft thread carriers

As shown in Figs. 4 and 13, a support or plate 60 carrying a series of weft thread carriers 62 is slidably arranged in the frame of the machine for reciprocating movements longitudinally of the machine in front of the needle beds. Cones 63 mounted on the machine supply a weft thread 64 to the thread tube 61 at the end of each weft thread carrier 62. The weft threads 64 serve for taking away entirely or partially the elasticity in the width of the fabric and at the same time for patterning the front side of the fabric. At the right hand side of the machine, the plate 60 is pivotally connected with one end of a connecting rod 65, the other end of which is pivoted to the upper end of a rockable arm 66, the lower end of which is swingably mounted on the frame of the machine at 67 (see Figs. 2, 15 and 16). When the arm 66—which may be rocked by a mechanism to be described hereinafter—is at a standstill, no thread is laid by the weft thread carriers 62. When a large stroke of the arm 66 is adjusted, a broad or even complete laying of weft thread is obtained, whereas when a small stroke of said arm 66 is adjusted, the weft threads are laid only through short distances. It will be readily understood that thus patterns with or without different color threads may be made independently of the pattern, that may be obtained by the zigzag knitting by means of the reciprocating warp guide bars.

As shown in Fig. 4, the weft thread carriers 62 are provided with adjustable resilient weft thread guides at their ends remote from the needles. The plate 60 with the weft thread carriers is moved in such a manner that when the needles in the front bed are in their lowest position, the plate is moved to the right through a certain distance, whereby a weft thread 64 is laid behind the hooks of the needles by the thread tubes 61. When now the needles are moved upwardly, said weft thread is lying still loose behind the needles. When the needles again come into their lowest position, a knitted stitch glides from each needle, so that the previously laid weft thread 64 comes to lie between the stitches of the front bed and back bed. As soon as this feature has taken place, the carrier is moved to the left, whereby again a weft thread is laid behind the hooks of the needles, and so on. The number of weft thread carriers 62 is chosen in such a manner that for a certain stroke of the plate 60 just the entire width of the needle beds is covered.

Adjustment of the stroke of the weft thread carriers

As shown in Fig. 16, the main shaft 4 drives through the medium of bevel gears a shaft 68 carrying a pinion 69 meshing with a gear 70. Said gear 70 and a disc or cam 71 (see Fig. 15) having a cam path 72 form a unitary structure. Thus, the cam 71 rotates continuously and in synchronism with the movements of the needles and the warp guide bars. A pin 73 carried by a slide 74 guided by a stationary part 75 mounted on the frame of the machine is slidably engaged

with the path 72 of said cam 71. The slide 74 reciprocable in a substantially vertical direction is pivotally connected with the lower end of a connecting rod 76, the upper end of which is pivoted at 77 to an automaton or automatic device 78 rockably mounted on the machine at 79.

The arm 66 connected in above described manner with the weft thread carriers carries a pin 80 slidably engaged with a slot 81 of a disc 82, the varying angular position of which is determined by a mechanism to be described hereinafter.

Now, assume that said mechanism determining the angular position of the disc 82 is at a standstill: Upon rotation of the cam 71, at first the arm 66 will remain at a standstill as long as the pin 73 is engaged with a concentric portion of the cam path 72. During this standstill of the arm 66, the needles may form loops of the crossing warp yarns. As soon as the pin comes into engagement with a non-concentric portion of the cam path 72, the slide 74 is moved upwardly by the pin 73, so that the automatic device 78 is tilted in clockwise direction as viewed in Fig. 15. Said tilting of the automaton in turn causes a displacement of the pin 80 of the arm 66 to the left by the wall of the slot 81 of the grooved disc 82, whereby the arm 66 is swung in counter-clockwise direction. Obviously, when during the continuation of the rotation of the cam 71 the pin 73 comes into engagement with the complementary non-concentric portion of the cam path 72, the arm 66 will be swung back in clockwise direction. The slot 81 may be positioned in such a manner, that the arm 66 is not subjected to an effective displacement. The position of the slot 81 is determined by a wormwheel 83 rigidly connected with the disc 82 and in mesh with a worm 84 keyed to a shaft rotatably mounted on the automatic device 78. A pinion 85 in mesh with a gear 86 is keyed to the other end of said shaft. Said gear 86 is mounted on a rotatable shaft carrying also a smaller gear 87. Either the pinion 88 or the pinion 89 or none of said two pinions of a set of three pinions 88, 89, 90, of which the pinion 90 meshes with the pinion 88 and the pinion 88 meshes with the pinion 89, may be brought automatically into mesh with said gear 87. For this purpose, said three pinions are rotatably arranged in a holder 92 swingably arranged on the shaft carrying the pinion 90. Said holder 92 may be swung automatically about its pivot in a manner to be described hereinafter.

A spring 93 (Fig. 16) stretched between the holder 92 and the frame of the automatic device 78 tends to swing the holder always in counter-clockwise direction against a stop secured to the frame of the automatic device. The holder 92 is provided with a nose 91 in engagement with a cam 94 having a series of interexchangeable cam segments and being keyed to a shaft rotatably arranged on the frame of the automatic device. A gear 95 in mesh with the pinion 90 of the set of pinions 90, 88, 89 is likewise keyed to said shaft carrying the cam 94, so that said gear 95 participates in the movements of said cam 94. The cam 94 and gear 95 may be intermittently advanced in counter-clockwise direction (as viewed in Fig. 16) by means of a ratchet device 96 which is actuated by the shaft 68 through the medium of a crank pin 97 and a connecting rod 98. Said crank pin 97 is adjustably engaged with a slot of a disc secured to the shaft 68. Therefore, the position of the holder 92 is automatically adjusted by the intermittently advanced cam 94 engaged with the nose 91 of

said holder. Obviously, depending on the shape of the camming surface of the cam 94, the holder 92 is brought either into a position wherein the pinion 88 meshes with the gear 87 as shown in Fig. 16, or into a position wherein the pinion 88 meshes with the gear 95 whereby upon a rotation of the gear 95 in the same sense as before the rotation of the gear 87 is reversed, or into a position wherein neither one of the pinions 88 and 89 is in mesh with the gear 87 whereby upon a rotation of the gear 95 the gear 87 remains at a standstill.

During the repeated tilting back and forth of the automatic device 78 by means of the cam 74, slide 74 and connecting rod 76, the cam 94 controlling the position of the holder 92 and the gear 95 are intermittently advanced by the ratchet device 96. During each advancing step of the gear 95 the pinion 88 is advanced in counter-clockwise direction and the pinion 89 is advanced in clockwise direction. Depending on the position of the holder 92 controlled by the cam 94, consequently, the slot 81 of the disc 82, engaged with the pin 89 of the arm 66 is either advanced in clockwise direction, or in counter-clockwise direction, or not at all. Said displacement or non-displacement of the slot 81 in turn results either in an increase or decrease or no change or reversal of the rocking movement of the arm 66 caused by the continuous automatic tilting of the automatic device 78. Apparently, during such a displacement of the slot 81 of the disc 82, the slot 81 may be brought into a position wherein the arm 66 remains practically at a standstill in spite of the tilting of the automatic device 78. As mentioned above, the arm 66 in turn controls the stroke of the weft thread carriers 62. Therefore, all kinds of variations in the design of the weft thread may be obtained by the automatic device and its control described above.

The present invention relates not only to the machine as described and illustrated and its method of operation, but also to all technically equivalent embodiments, modifications and improvements thereof. It is possible to knit with all needles at one side and thus make a fabric with a front and a back, in deviation of the fabric manufactured on the illustrated machine and having at both sides the same appearance. Also it is possible to lay the weft thread in a different manner and to knit it in differently.

By warping the warp beams in correspondence with the stroke length of the warp guide bars and possibly with that of the weft thread carriers, various patterns may be obtained. As appears from the foregoing no use is made of a Jacquard device, of knitting cams, closed eye needles or spring beard needles, but exclusively of latch needles moving simultaneously.

By replacing the eccentric discs or cams 57 (Figs. 9 and 18) by others the zigzag width may be changed and the warp yarn crossings may be offset over one needle or over two or more needles.

The plate 60 carrying the weft thread carriers 62 may be arranged at the back of the machine instead of at the front, as far as the thread supply permits this arrangement. If desired, more than one plate provided with weft thread carriers may be used.

Instead of two separate warp beams for each needle bed one warp beam or more than two warp beams may be used.

What I claim is:

1. A warp knitting machine, comprising: two needle beds arranged at an acute angle relative

to each other, each needle bed including a series of spaced reciprocable latch needles, the needles of one bed being arranged opposite the space between the needles of the other bed, a needle drive associated with the needles of both needle beds for reciprocating the series of needles of one needle bed at substantially the same rate but in opposite direction of movement to the movement of the needles of the other needle bed, two warp yarn guide bars, a series of yarn guiding means arranged on each warp yarn guide bar, said warp yarn guiding means being spaced from each other at substantially the same distance as the needles of a series of needles, warp yarn supplying means for supplying warp yarns to the yarn guiding means of said warp yarn guide bars, and a pattern mechanism associated with said warp yarn guide bars for displacing same relative to the series of needles at predetermined intervals in a predetermined manner so as to cause the formation of warp yarn crossings by means of said yarn guiding means and to present said warp yarn crossings alternately to the needles of one series of needles and to the needles of the other series of needles.

2. A warp knitting machine, comprising: two needle beds arranged at an acute angle relative to each other, each needle bed including a series of spaced reciprocable latch needles, the needles of one bed being arranged opposite the space between the needles of the other bed, a needle drive associated with the needles of both needle beds for reciprocating the series of needles of one needle bed at substantially the same rate but in opposite direction of movement to the movement of the needles of the other needle bed, two warp yarn guide bars, each of said warp yarn guide bars having a series of yarn guiding grooves spaced from each other at substantially the same distance as the needles of a series of needles, warp yarn supplying means for supplying warp yarns to the yarn guiding grooves of said warp yarn guide bars, and a pattern mechanism associated with said warp yarn guide bars for displacing same relative to the series of needles at predetermined intervals in a predetermined manner so as to cause the formation of warp yarn crossings by means of said yarn guiding grooves and to present said warp yarn crossings alternately to the needles of one series of needles and to the needles of the other series of needles.

3. In a warp knitting machine as claimed in claim 2, the yarn guiding grooves of both warp yarn guide bars facing the same side of the machine.

4. In a warp knitting machine as claimed in claim 1, said pattern mechanism including a first cam drive associated with one of said warp yarn guide bars and a second cam drive associated with the other warp yarn guide bar.

5. In a warp knitting machine as claimed in claim 1, adjustable positioning means interposed between the pattern mechanism and each of said warp yarn guide bars.

6. In combination with a warp knitting machine as claimed in claim 1, at least one auxiliary warp yarn guiding element, auxiliary warp yarn supplying means for supplying auxiliary warp yarn to said auxiliary warp yarn guiding element, said auxiliary warp yarn guiding element being reciprocable parallel to the series of needles, and a drive associated with said auxiliary warp yarn guiding element for reciprocating same.

7. In combination with a warp knitting ma-

11

chine as claimed in claim 1, at least one auxiliary warp yarn guiding element, and auxiliary warp yarn supplying means for supplying auxiliary warp yarn to said auxiliary warp yarn guiding element, said auxiliary warp yarn guiding element being reciprocable parallel to the series of needles, and said needle drive being coupled with said auxiliary warp yarn guiding element for reciprocating same.

8. In combination with a warp knitting machine as claimed in claim 1, an auxiliary warp yarn guiding element slidably arranged at each side of the machine adjacent to the ends of the series of needles, auxiliary warp yarn supplying means for supplying auxiliary warp yarn to said auxiliary warp yarn guiding elements, each of said auxiliary warp yarn guiding elements being reciprocable parallel to the series of needles, and a drive associated with said auxiliary warp yarn guiding elements for reciprocating same.

9. A warp knitting machine, comprising: two needle beds arranged at an acute angle relative to each other, each needle bed including a series of spaced reciprocable latch needles, the needles of one bed being arranged opposite the space between the needles of the other bed, a needle drive associated with the needles of both needle beds for reciprocating the series of needles of one needle bed at substantially the same rate but in opposite direction of movement to the movement of the needles of the other needle bed, two warp yarn guide bars, a series of yarn guiding means arranged on each warp yarn guide bar, said warp yarn guiding means being spaced from each other at substantially the same distance as the needles of a series of needles, warp yarn supplying means for supplying warp yarns to the yarn guiding means of said warp yarn guide bars, a first pattern mechanism associated with said warp yarn guide bars for displacing same relative to the series of needles at predetermined intervals in a predetermined manner so as to cause the formation of warp yarn crossings by means of said yarn guiding means and to present said warp yarn crossings alternately to the needles of one series of needles and to the needles of the other series of needles, a support slidably arranged on the machine, a series of weft thread carriers mounted on said support, said support with said weft thread carriers being reciprocable parallel to the series of needles, and a second pattern mechanism associated with said support for controlling movements thereof.

10. In a warp knitting machine as claimed in claim 9, said second pattern mechanism including an automatic device adjusting automatically

12

the stroke and direction of movement of said support.

11. A warp knitting machine as claimed in claim 9, wherein said second pattern mechanism comprises: a swingable automatic device, a first power driven cam associated with said automatic device for tilting same at predetermined intervals, in alternate directions, a disc having a slot rotatably mounted on said automatic device, a swingable arm connected to said support, a pin arranged on said arm and slidably engaged with the slot of said disc, a power driven ratchet drive mounted on said automatic device, a second cam and a first gear rigidly connected with each other and jointly driven by said ratchet drive, a holder swingably mounted on said automatic device, a set of pinions comprising a first pinion meshing with a second pinion which in turn meshes with a third pinion rotatably arranged in said holder, said first pinion meshing with said first gear, a second gear rotatably mounted on said automatic device and coupled with said disc having said slot for adjusting same by rotation, said second cam cooperating with said holder for adjusting same in alternative positions wherein either said second pinion or said third pinion or no pinion is in mesh with said second gear whereby said disc with said slot may be rotated in one or the other direction or may be held at a standstill for control of the stroke and direction of movement of said arm connected with said support.
